COMPARTMENT DOOR LATCH

Edward N. Jacobi, Milwaukee, Wis., assignor to
 Briggs & Stratton Corporation, Milwaukee,
 Wis., a corporation of Delaware

Application July 27, 1942, Serial No. 452,433

10 Claims. (Cl. 292—227)

This invention relates to door latches, and particularly to latches of the type designed for use with automobile glove compartment doors forming the subject matter of the copending application of Edward N. Jacobi, Serial No. 403,122, filed July 19, 1941, and matured into Patent No. 2,301,282, of November 10, 1942.

The latch device of the aforesaid copending application has a formed sheet metal push button, but the housing or body as well as the bolt are die castings.

The present invention contemplates as one of its objects the provision of a latch device of this type wherein all of the parts thereof are sheet metal stampings to thus materially reduce the cost and produce a stronger construction.

In this connection it is another object of this invention to provide a latch device having a sheet metal frame or housing stamping so designed and constructed as to permit the same to be made in two simple press operations, one a blanking and piercing operation and the other a forming operation.

In latch devices of this type the bolt is pivotally mounted in the housing frame member and is spring pressed to an operative position projecting a portion thereof from the housing for engagement with a striker plate or keeper. Depression of a push button operatively connected with the bolt retracts the projecting portion to free the door for opening.

In the present instance the bolt is mounted on a pivot pin the ends of which are received in sockets formed in the housing or frame member and it is a particular object of this invention to provide a novel manner of forming these sockets by which assurance is had against deformation of the sockets during the forming operation and by which the pivot pin may be directly supported to facilitate a staking operation by which the pin is secured against endwise shifting.

Another object of this invention is to provide an interconnection between the push button and bolt by which a simple hole pierced in the front wall of the frame or housing in cooperation with the connection between the bolt and push button satisfactorily mounts and guides the push button.

Another object of this invention resides in the provision of means incorporated in the connection between the bolt and push button by which the push button is restrained against rotation.

Another object of this invention is to so mount the bolt spring that it reacts against the push button to hold it as well as the bolt against rattling.

With the above and other objects in view, which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate one complete example of the physical embodiment of the invention constructed according to the best mode so far devised for the practical application of the principles thereof, and in which:

Figure 1 is a perspective view of a latch device constructed in accordance with this invention;

Figure 2 is a rear end view thereof;

Figure 3 is a longitudinal sectional view through the latch device showing the same mounted on a compartment door and holding the door closed;

Figure 4 is a view similar to Figure 3 but showing the manner in which depression of the push button retracts the latch bolt and frees the door for opening; and

Figure 5 is a perspective view illustrating the inner end portion of the push button and the latch bolt to show the manner in which the interconnection therebetween is effected.

Referring now particularly to the accompanying drawings, in which like numerals indicate like parts, the numeral 5 designates the door of a glove compartment only the upper wall 6 or ceiling of which is illustrated. However, as is well known, the compartment is generally located behind the instrument panel of an automobile.

Extending down from the upper wall or ceiling 6 is a striker plate 7. This striker plate is in position to be engaged by the bolt 8 of a latch device indicated generally by the numeral 9 and mounted on the door so that when the door is closed the bolt automatically engages behind the striker plate.

The latch comprises a stamping 10 which forms the housing member or frame member of the device and has angularly disposed top and front walls 11 and 12, respectively. These walls are preferably disposed at right angles to each other and their juncture is reinforced by brace-like indentations 13.

The side and rear edges of the top wall are bent down to provide side flanges 14 and a rear wall 15, the latter serving as a protection against interference with operation of the latch mecha-

nism by the contents of the glove compartment which are often crowded in.

The front wall 12 has a round hole 16 therethrough and is preferably embossed to provide an annular collar 17 surrounding the hole and projecting out a slight distance from the front wall.

The top wall 11 has a rectangular hole 18 therein and on opposite sides of this rectangular hole and at the bent corners formed by the junctures of the top with its side flanges 14 are notches or openings 19. These notches or openings 19 extend around the corners as shown so that part thereof lies in the top wall and the remainder in the side flanges. That portion of 15 the notches which lies in the flanges 14 has a round bottom to snugly receive the end portions of a pivot pin 20 upon which the bolt 8 is mounted.

In addition to the hole 16 and the embossed 20 collar 17 the front wall 12 has two holes 21 therethrough which fastening means pass for mounting the latch on the back of the door.

Attention is particularly directed to the fact that the housing member or frame member is so designed and constructed that it requires only two simple press operations. The stamping needs only to be pierced and blanked in one die and its four edges bent up in another to complete the part.

The notches or openings 19 which serve as sockets for the ends of the pivot pin extend around the bent corners at the junctions of the top wall with its side flanges for two reasons: First, this design avoids the distortion that would take place if a round hole were pierced in the blank and then the blank bent closely adjacent to the hole. This would cause the hole to be pulled partly around the bend resulting in distortion so that it would no longer fit the pin.

On the other hand, if the holes were to be produced after the flanges were bent, extra operations would be required as burrs would have to be removed and it would be difficult to locate the holes tangent to the inside face of the top wall as desired.

Second, the elongated holes 19 provide access to the end portions of the pin so that the pin can be directly supported while it is staked to form protrusions or extensions 22 directly inside the side flanges and by which the pin is restrained against endwise displacement.

Not only does the present manner of assembling the pin with the housing member or frame member result in simpler and less expensive construction, but also it improves the appearance of the device as the pin needs no projecting heads to retain the same in place.

The bolt 8, like the housing member or frame member, is a steel stamping and as best illustrated in Figure 5 is formed with two arms 23 and 24 disposed at an acute angle to each other. The arm 23 is channel shaped in cross section having side flanges 25 joined by a web 26 the outer end of which is turned down to form a 60 striker engaging surface 27.

The pivot pin by which the bolt is mounted passes through holes 28 in the side flanges, the holes being so located that when the bolt is retracted as shown in Figure 4, its outer end is 70 brought down flush with the top wall.

The side flanges 25 are extended as shown in Figure 5 to form the arm 24. At the juncture of the two arms, i. e., at the inner apex or point of the V formed by the two arms, are flat sur-

faces 29. These flat surfaces formed by the inner edges of the side flanges are substantially radial to the axis of the holes 28 and are spaced outwardly therefrom so that upon the application of pressure on these surfaces, the latch bolt is rocked on the pivotal mounting in a direction to retract the same.

Such pressure is applied to the latch bolt by a push button 30. The push button 30 is similar in construction to the button forming the subject matter of the aforesaid copending application in that it is formed entirely of sheet metal rolled into a tube and provided with a cap 31 on its outer end.

The push button is slidably received in the hole 16 and is held against outward displacement by a spring stop 32 mounted in the push button and engaging the back of the front wall. This spring stop and the manner of its securement forms part of the subject matter covered by the aforesaid copending application.

As distinguished from the latch device of said copending application, the push button in this instance requires no elaborate guide, as its inner tubular end has a novel connection with the latch bolt by which support is provided for the bolt. To this end the arm 24 of the latch bolt formed by the extensions of its side flanges projects into the rear open end of the bolt and the flanges receive therebetween a rearwardly projecting tongue 33 extended from the push button. The engagement of the tongue 33 between the side flanges of the bolt holds the button against turning and as will be readily apparent the shoulders 29 are engaged by the rear edges 34 of the push button directly adjacent to its tongue 33.

The arm 24 of the bolt is long enough to preclude accidental disengagement thereof from the push button. Hence, through the support of the push button by arm 24 and the hole 16, the push button is satisfactorily guided and mounted for its required substantially axial movement.

45 A torsion spring 35 coiled about the pivot pin between the side flanges of the bolt with one end thereof bearing against the under face of the bolt arm 23 and its opposite end reacting against the side of the push button yieldingly urges the bolt to its operative position at which the arm 23 projects through the hole 18 into the path of the striker plate 7.

The action of the spring also projects the push button outwardly to the limit of its movement except when the bolt engages behind the striker plate as when the door is closed. But at all times the reaction of the spring against the side of the push button holds the push button as well as the bolt against rattling.

From the foregoing description, taken in connection with the accompanying drawings, it will be readily apparent that this invention provides a latch device which is less expensive and also stronger than those heretofore in use on automobile glove compartment doors.

What I claim as my invention is:

1. In a latch device of the character described: a housing member having a front wall with a hole therethrough; a push button slideable in said hole; means on the push button engageable with a part of the housing member for limiting outward projection of the push button, the inner end portion at least of the push button being tubular; a latch bolt having angularly disposed arms; means pivotally mounting

the latch bolt on the housing member behind its front wall to swing about an axis passing through the apex of the bolt and substantially parallel with the front wall and to one side of the path of the push button, and a spring acting on the latch bolt and biasing the same to an operative position, at which one of its arms protrudes from the housing member for engagement with a keeper, and the other arm projects into the tubular end of the push button, the inner edges of the arms of said bolt being shaped to provide a shoulder so spaced from the pivot axis of the latch bolt that pressure applied by the push button against said shoulder retracts the bolt against the action of its spring, and the arm of the bolt which projects into the push button being long enough to preclude disengagement thereof from the push button.

2. In a latch device of the character described: a housing member having a front wall with a hole therethrough to slideably receive a push button and having pivot sockets rearwardly of the front wall; a latch bolt having angularly disposed arms forming substantially a bell-crank lever; a pivot pin in the sockets mounting the latch bolt at its apex; a spring biasing the latch bolt to a position at which one of its arms projects from the housing member for engagement with a keeper and its other arm projects forwardly toward the front wall substantially in line with the hole therein; a pressure receiving shoulder in the crotch of the bolt facing the front wall and spaced radially from the pivot axis of the bolt; and a push button slideable in the hole through the front wall of the housing member, the inner end portion of the push button being tubular and having the adjacent forwardly projecting arm of the latch bolt received therein, so as to place the shoulder against the end of the push button, said interengagement of the bolt and push button cooperating with the hole in the front wall in guiding the push button.

3. In a latch device of the character described: a housing member having angularly disposed walls one of which has a push button receiving hole therethrough and the other of which has a hole for the reception of a latch bolt; means on said last named wall providing pivot sockets at opposite sides of its hole; a latch bolt; a pivot for the bolt received in said sockets; said latch bolt having angularly disposed arms one of which is a keeper engaging arm projectible through said bolt receiving hole and the other of which is directed toward the front wall substantially in line with the hole therein; a push button slideably received in the hole in the front wall with its inner end interconnected with the arm of the bolt projecting forwardly toward the front wall; a shoulder at the base of the forwardly projecting arm of the bolt spaced radially from its pivot axis and engageable by the push button so that the pressure applied on the push button rocks the bolt on its pivot; and a spring acting on the bolt and biasing the same to an operative position at which the push button is yieldingly held out by the bolt and the keeper engaging arm of the bolt projects through the bolt receiving hole for engagement with a keeper.

4. In a latch device of the character described; a housing member having angularly disposed walls one of which has a push button receiving hole therethrough and the other of which has a hole for the reception of a latch bolt; means on said last named wall providing pivot sockets at opposite sides of its hole; a latch bolt; pivots

for the bolt received in said sockets; said latch bolt having angularly disposed arms one of which is a keeper engaging arm projectible through said bolt receiving hole and the other of which is directed toward the front wall substantially in line with the hole therein; a push button slideably received in the hole in the front wall with its inner end interconnected with the arm of the bolt projecting forwardly toward the front wall; a shoulder at the base of the forwardly projecting arm of the bolt spaced radially from its pivot axis and engageable by the push button so that the pressure applied on the push button rocks the bolt on its pivot; and a spring acting on the bolt and biasing the same to an operative position at which the push button is yieldingly held out by the bolt and the keeper engaging arm of the bolt projects through the bolt receiving hole for engagement with a keeper; said spring reacting against the push button to hold the same against rattling.

5. In a latch device of the character described: the combination of a pivoted latch bolt having angularly disposed arms with a pressure receiving shoulder at the base of one of the arms, said shoulder being spaced radially from the pivot axis of the bolt; a tubular push button having said arm of the bolt received in its inner end with part of the rear edge of the push button engageable with said shoulder to rock the bolt on its pivot upon depression of the push button; and a bolt spring confined between the bolt and the push button.

6. In a latch device of the character described: a housing member comprising a stamping having angularly disposed front and top walls; the front wall having a hole for the reception of a push button and the top wall having a hole to accommodate a latch bolt; flanges on the side edges of the top wall; and pivot pin sockets to receive the pivots of a latch bolt; said sockets being formed by notches in the bent corners at the junctures of the top wall with its side flanges, said notches being of sufficient size to extend around the bent corners.

7. As an article of manufacture: a stamped sheet metal housing member for latch devices of the type used on glove compartment doors of automobiles, said housing member having angularly disposed front and top walls, the top wall having a bolt receiving hole one end of which is adjacent to the front wall; down-turned flanges on the side edges of the top wall; notches in the bent corners at the junctures of the top wall and its side flanges at opposite sides of the bolt receiving hole, said notches extending around the bent corners so that a pivot pin for the latch bolt received therein is accessible from above the top wall and so that the notches are not deformed as the flanges are bent down from the top wall; and the front wall having a push button receiving hole and attaching ears by which the housing may be secured to a supporting panel.

8. In a latch device of the character described: a stamped sheet metal housing member having a top wall with a bolt receiving hole therethrough; flanges on the sides of the top wall at opposite sides of the bolt receiving hole; a latch bolt; a pivot pin for the latch bolt; pivot sockets in the side flanges of the top wall having the ends of pin received therein; said pivot sockets extending around the bent corners at the junctures of the top wall with its side flanges so that the ends of the pivot pin are accessible from above the top wall; and protrusions on the end

portions of the pivot pin directly adjacent to said side flanges to hold the pin against axial displacement, the accessibility of the pivot pin end portions from above the top wall enabling direct support of the pin during the formation of said protrusions.

9. In a latch device of the character described: a housing member; a push button mounted in the housing member for axial movement, at least the inner end portion of the push button being tubular; a tongue projecting from the inner end of the push button; and a latch bolt pivoted on the housing member and having angularly disposed arms forming a bell-crank lever with the pivot for the bolt at the apex of the lever, one of the arms of the bell-crank shaped bolt projecting into the rear end of the push button, said projecting arm of the bolt having spaced flanges between which the projecting tongue on the push button is received whereby the push button 20 is restrained against turning.

10. In a latch device of the character described, the combination of: a pivoted latch bolt having angularly disposed arms with a pressure receiving shoulder at the juncture thereof, said shoulder being spaced radially from the pivot axis of the bolt which is adjacent to its apex; a tubular push button having one arm of the bolt received in its inner end so that part of the rear edge of the push button is engageable with said bolt to rock the bolt on its pivot upon depression of the push button; a supporting wall having a hole in which the front end portion of the push button is slideably received, said supporting wall cooperating with the arm of the bolt projecting into the inner end of the push button to guide and mount the push button; and a spring biasing the bolt to an operative position at which the push button is projected outwardly.

EDWARD N. JACOBI.
